UNITED STATES PATENT OFFICE.

FELIX SCHWERDTFEGER, OF POSEN, GERMANY.

CALENDAR.

No. 801,112.

Specification of Letters Patent.

Patented Oct. 3, 1905.

Application filed May 19, 1905. Serial No. 261,281.

To all whom it may concern:

Be it known that I, FELIX SCHWERDTFEGER, a subject of the German Emperor, residing at Posen, Germany, have invented new and useful Improvements in Calendars, of which the following is a specification.

The object of my invention is to provide a simple, cheap, and convenient perpetual calendar which is applicable to a pen, pencil, or other like object and is readily adjustable to determine the day of the week of any given date in a series of years.

The preferred embodiment of the invention is illustrated in the accompanying drawings, 15 in which—

Figure 1 is a plan view of the calendar applied to a pen or pencil. Fig. 2 is a plan view of the calendar-section forming the inner stationary cylinder. Figs. 3 and 4 are similar 20 views of the calendar-sections composing the two outer cylinders, and Fig. 5 is a cross-section taken on line 5 5 of Fig. 1.

The calendar comprises three parts or sections A, B, and C, which may be mounted 25 upon a pen, pencil, or other suitable supporting object D. The part A consists of a tablet or strip of flexible material rolled into cylindrical form and suitably secured to the periphery of the support D. The upper portion 30 of this part A is ruled to provide transverse and longitudinal columns a' , forming blocks or spaces a^2 , which with certain exceptions contain the suffix or terminal numerals of the years, beginning in the present instance with "00" and ending with "27," thus covering a corresponding term of years. The numerals extend transversely from left 35 to right in columns of six in regular order, and some of the blocks are left blank or dotted, as shown, according to the requirements of the system of calculation, while those blocks carrying the numerals of leap-years are designated by hatching or suitably coloring them. A table A' is thus produced, 40 which for convenience of description may be termed a "suffix" year-table.

At the bottom of the strip A is a month-table A², having blocked longitudinal and transverse columns a^3 a^4 similar to the table 45 A', the names of the months being irregularly arranged in certain of the blocks in a desired manner, while the blocks which are unoccupied by month-names are left blank or crossed out by an $\times$ or cross-mark. It will be observed that the month-names "Jan." and 50

"Feb." are duplicated, the duplicate names being disposed in the hatched or colored spaces a^5 and properly arranged to be used when the year on which the calculation is based is a leap-year. 60

The part B comprises a cylindrical strip which surrounds the table A' and is used in conjunction therewith. It is provided in its upper portion with a longitudinal observation-slot b, at one side of which is a table b' 65 containing the prefix year of the current century—to wit, "19"—and below which is a transverse table b² containing the names of the days of the week.

The part C consists of a cylindrical strip 70 similar to the strip B and surrounds the lower portion of the cylinder A. In the lower portion of this part C is a longitudinal slot c and above the same a table C', ruled to form blocked transverse and longitudinal columns 75 c' and c^2 , containing the numerals "1" to "31," inclusive, designating days of the month. The transverse columns c' extend obliquely, so that the numerals therein will be arranged spirally about the supporting object D when 80 the part C is applied thereto, as shown in Fig. 1.

The part or cylinder A is stationary on the support D, as above described, while the cylinders B and C are revolvable, so that they may 85 be adjusted to make the desired calculations.

The mode of using the calendar is as follows: If it be desired, for instance, to determine on what day of the week March 4, 1904, fell, the cylinder B is turned until the year suffix "04" 90 on the table A' is exposed through the slot b and the cylinder C turned until the abbreviation "Mar." in the table A² is exposed through its slot c, whence it will be apparent, as the slots b and c then register with the word "Friday" in the table b², that March 4, 1904, fell on that day of the week. All the remaining dates of the month of March will then stand under the proper week-day names. In addition to the abbreviation "Mar." the slot c will 95 also expose the abbreviations for the months February and November, which in ordinary years have the same distribution of days as March. As 1904 is a leap-year, however, the exposed abbreviation "Feb." in the plain 100 block or space will not indicate the true distribution of days in February for that year, the month-names in the spaces a^5 being used in making calculations for January and February for this and all other years which are 110

leap-years. This being understood, the mode of adjusting the calendar for making any calculation within the period covered by the calendar will be apparent.

5 The calendar, as shown, covers a period of twenty-eight years, and is therefore practically perpetual, since it is simply necessary at the end of each period to change the year-numbers of the part A to accord with the new relations 10 between the months and years, which change every twenty-eight years.

Having thus described the invention, what is claimed as new is--

15 1. A calendar comprising three members, one of the members having a year-suffix table and a month-table, the second member having a week-day table, a year-prefix table and an observation-slot alongside the latter table, said 20 second member being adjustable to coöperate with the year-suffix table on the first-named member, and a third member having a month-day table and an observation-slot and adjustable so as to adapt the slot to coöperate with the month-table on the first-named member, substantially as described.

the month-table on the first-named member, substantially as described.

2. A calendar comprising three members, one of the members being provided with a year-suffix table having suitable designations for the leap-years, and a month-table having 30 duplications for the first two months for leap-year use, the second member having a week-day table, a year-prefix table and an observation-slot alongside the latter table, said second member being adjustable to coöperate with the year-suffix table on the first-named member, and a third member having a month-day table and an observation-slot and adjustable so as to adapt the slot to coöperate with the month-table on the first-named member, substantially as described.

35 In testimony whereof I affix my signature in presence of two witnesses.

FELIX SCHWERDTFEGER. [L. s.]
